UNITED STATES PATENT OFFICE.

HERMANN MEYER, OF NEW YORK, N. Y.

CONTROLLING MECHANISM.

No. 900,408.

Specification of Letters Patent.

Patented Oct. 6, 1908.

Application filed December 27, 1907. Serial No. 408,293.

To all whom it may concern:

Be it known that I, HERMANN MEYER, a citizen of the United States, and a resident of the city of New York, borough of the Bronx, in the county and State of New York, have invented a new and Improved Controlling Mechanism, of which the following is a full, clear, and exact description.

The invention relates to self-playing pianos and like musical instruments, and its object is to provide a new and improved controlling mechanism, arranged to control independently the tempo, action, expression, the damper and the hammer rail, in a very simple and efficient manner.

The invention consists of novel features and parts and combinations of the same, which will be more fully described herein-after and then pointed out in the claims.

20 A practical embodiment of the invention is represented in the accompanying drawings forming a part of this specification, in which similar characters of reference indicate corresponding parts in all the views.

25 Figure 1 is a front elevation of the improvement as applied to a self-playing piano, parts of the latter being omitted; Fig. 2 is an enlarged transverse section of the same, on the line 2—2 of Fig. 1; Fig. 3 is 30 an enlarged edge view of one of the controlling levers, and Fig. 4 is a rear sectional elevation of the same, on the line 4—4 of Fig. 3.

The hand-lever A has its hollow shaft A' extending transversely and journaled in suitable bearings on the bottom of the key board B, and on the said shaft A' is secured an arm A² pivotally connected with the stem C' of the mechanical valve C controlling the speed of the note sheet in the usual manner. On the hand-lever A is fulcrumed the lever D carrying a valve D' controlling an air port a leading to the interior of the hollow shaft A', the said lever D being 40 pressed on by a spring D², to normally hold the valve D' in a closed position. The rear end of the hollow shaft A' is connected by a tube E with a pneumatic valve F connected with the wind chest and by a pipe 45 F' with a pneumatic G controlling a lever H for actuating the damper rail H' in the usual manner, that is, actuating the damper rail H' for removing the damper from the strings whenever the pneumatic G is collapsed. This takes place when air is admitted to the valve F by way of the tube E,

the hollow shaft A' and port a, opened by the operator pressing the lever D correspondingly.

Now from the foregoing it will be seen that the operator having hold of the hand-lever A can conveniently swing the lever to the right or left, so as to actuate the valve C employed for controlling the speed of the note sheet, and the operator having hold of the lever A can also press the lever D to swing the valve D' into an open position, thus admitting air to the valve F, with a view to actuate the pneumatic G, lever H and damper rail H', to remove the dampers from the strings the same as if the loud pedal had been pressed. As soon as the operator releases the pressure on the lever D, the spring D² thereof closes the valve D' so that the pneumatic G is allowed to inflate and the damper rail H' is moved back to normal inactive position.

On the front of the instrument and to the left of the lever A is arranged a second hand-lever I secured on a hollow shaft I', extending transversely and journaled on the bottom of the key board B, the rear end of the said shaft I' being provided with an arm I² connected with the stem J' of the valve J employed for controlling the action pneumatics to give the desired expression. On the hand-lever I is fulcrumed a lever L carrying a valve L' controlling a port similar to the port a and leading to the hollow shaft I', the said valve being normally in a closed position by the action of a spring L² pressing on the lever L, the same as the spring D² acting on the lever D, as above mentioned. The rear end of the hollow shaft I' is connected by a tube N with a pneumatic valve O connected with the wind chest, and by a pipe O' with a pneumatic P, employed for imparting a swinging motion to the lever Q, controlling the hammer rail R, which latter normally is in an inactive position. Now by the arrangement described, the operator having hold of the lever I with the left hand can impart a swinging motion to the said lever, to actuate the mechanical valve J, with a view to control the expression, as previously mentioned, and at the same time the operator can press the lever L, to open the valve L', thereby admitting air to the hollow shaft I', and by way of the tube N to the pneumatic valve O, to connect the wind chest with the pipe O' and the pneumatic P, to cause the latter to

collapse and in doing so to impart a swinging motion to the lever Q for moving the hammer rail R into an active position, the same as if the soft pedal had been pressed by the player. When the operator releases the lever L, then the spring L² thereof causes the valve L' to close the port leading to the hollow shaft I', so that air is cut off from the pneumatic valve O, and consequently the pneumatic P is allowed to again inflate, thus returning the lever Q and the hammer rail R to normal dormant position.

From the foregoing it will be seen that the operator having hold of the lever A with the right hand and of the lever I with the left hand, can readily manipulate the said levers and at the same time can also press the levers D and L without removing the hands from the levers A and I. As the levers D and L control the damper and hammer rail, respectively, it is evident that the operator can conveniently and independently produce the desired tempo, give the desired expression and graduate the tone, soft or loud as the music may call for.

Having thus described my invention, I claim as new and desire to secure by Letters Patent:

1. A self-playing piano provided with an expression valve, a pneumatically operated valve, a hand lever, a hollow shaft for the said hand lever connected with the said expression valve to actuate the latter on imparting a swinging motion to the said hand lever, the said hollow shaft having its conduit connected with the said pneumatically operated valve, the said hollow shaft hav-

ing an air port and a manually-controlled lever valve mounted on the said hand lever and controlling the said air port to control the said pneumatically operated valve.

2. A self-playing piano provided with a damper rail, a hand lever, a hollow shaft for the said hand lever and provided with an air port, a valve for controlling the speed of the note sheet and mechanically connected with the said hollow shaft, a pneumatically operated valve for controlling the said damper rail and connected with the conduit of the said hollow shaft, and a manually-controlled self-closing lever valve fulcrumed on the said hand lever and controlling the said air port to actuate the said pneumatically operated valve.

3. A self-playing piano provided with a hammer rail, a hand lever, a hollow shaft for the said hand lever provided with an air port, a valve for controlling the action pneumatics and mechanically connected with the said hollow shaft, a pneumatically operated valve for controlling the said hammer rail and connected with the conduit of the said hollow shaft, and a manually-controlled self-closing lever valve fulcrumed on the said hand lever and controlling the said air port to actuate the said pneumatically operated valve.

In testimony whereof I have signed my name to this specification in the presence of two subscribing witnesses.

HERMANN MEYER.
